[57] CLAIM

The ornamental design of a combined granulator, dryer and coater, substantially as shown.

DESCRIPTION

FIG. 1 is a front elevational view of a combined granulator, dryer and coater showing my new design;

FIG. 2 is a side elevational view taken from the left of FIG. 1;

FIG. 3 is a rear elevational view thereof;

FIG. 4 is a side elevational view taken from the right of FIG. 1, shown partially broken away for clarity of illustration;

FIG. 5 is a top plan view thereof;

FIG. 6 is a bottom plan view thereof.
